UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT.

CASKET HANDLE.

Application filed February 28, 1921. Serial No. 448,296.

To all whom it may concern:

Be it known that I, EDWARD R. SARGENT, a citizen of the United States, residing in the city and county of New Haven, State 5 of Connecticut, have invented certain new and useful Improvements in Casket Handles, of which the following is a full, clear, and exact description.

This invention relates to casket handles, 10 and more particularly to that type of handle wherein the handle bar is suspended from the socket plates which are attached to the body of the casket by a pair of pivoted arms. The invention, moreover, has to do 15 particularly with the means of attaching the handle bar to the pivoted arms, and is shown and described as applied to a construction wherein the supporting arm and tip are cast in one piece, although it will be understood 20 that in some aspects of the invention, the same is applicable to other forms of handles.

The connection between the arm and the bar has heretofore been effected by means 25 of a screw or pin or the like, which is passed through a part of the arm through the metal of the tubular bar and secured within a wooden plug or the like, which is usually inserted within the bar. This form 30 of connection has the disadvantage that the wooden plug sometimes shrinks to some extent within a comparatively short time, and thereby loosening or impairing the connection between the arm and the bar. It is, therefore, expedient, when possible, to secure 35 the arm and the tubular bar together without the use of the wooden plug, both from the standpoint of economy and from the standpoint of securing an efficient connection.

40 One object of this invention is to provide a means for securing the pivoted arm directly to the tubular bar without the employment of a third member to connect the two.

A further object of the invention is to 45 obviate the use of the wooden plug heretofore referred to, which is usually used in connection with the tubular bar of the handle.

A still further object of the invention is 50 to provide interengaging means upon the bar and supporting arm, which, when the parts are assembled, may be locked with each other to secure them together so that all relative movement will be prevented.

55 A still further object of the invention is

to provide a new and improved means for connecting the handle bar to the tip and supporting arm when the latter two members are formed in one casting.

To these and other ends the invention consists in the novel features and combinations of parts to be hereinafter described and claimed.

In the accompanying drawings:

Fig. 1 is a front elevational view of a 65 casket handle embodying my improvements;

Fig. 2 is a rear elevational view of the same;

Fig. 3 is a rear detail view of one end of 70 the handle shown in Fig. 2;

Fig. 4 is a sectional view on line 4—4 of Fig. 3;

Fig. 5 is a view similar to Fig. 3, but showing a modified form of my invention;

Fig. 6 is a sectional view on line 6—6 of 75 Fig. 5;

Fig. 7 is a sectional view on line 7—7 of Fig. 4;

Fig. 8 is a sectional view on line 8—8 of 80 Fig. 6;

Fig. 9 is a sectional view similar to Figs. 7 and 8, but showing a still further modification of my invention;

Figs. 10 and 11 are fragmentary detail 85 views of one end of a casket handle similar to Figs. 3 and 5, but showing further modifications of my invention.

Fig. 12 is a partial view similar to Fig. 3 of a still further modification of my invention; and

Fig. 13 is a sectional view on line 13—13 of Fig. 12.

Referring to the drawings, the casket handle shown in Fig. 1 consists of the usual socket plates 10 to which are pivotally connected the arms 11, which, as shown, may be formed in one casting with the tips 12.

The supporting arms 11 and the tips 12 are usually formed or cast from the soft metal, which is more or less ornamental and which casting is usually provided with a strengthening brace 13, at the rear side of the arm. This strengthening brace may be embedded 95 in the soft metal portion of the arm, so that it is rigidly and firmly secured thereto. This brace, as well as the arm, is provided with a bore 14' at the lower portion thereof, which is adapted to slidably receive the tubular bar 15, which may be slipped through

100 the bore or loop of the brace until it con- 105 nects with the bore 14. The brace 13 is provided with a bore 14' at the lower portion thereof, which is adapted to slidably receive the tubular bar 15, which may be slipped through the bore or loop of the brace until it con- 110

tacts with the edge of the tip 12, as shown in Fig. 4. Usually the edge of the tip is formed with a shoulder 16 which limits the relative movement of the tip and bar in one direction. It will be obvious, as the description proceeds, that it is not always necessary to provide this shoulder which abuts against the end of the bar 15, but that the improved securing means, which will be hereinafter described, will be sufficient to hold the two members rigidly together.

The brace 13 is usually provided with the lug 14, which is struck up from the metal of the brace, and then turned at right angles to the plane of the members, as clearly shown in Fig. 3. A screw or pin has usually been passed through this lug in the devices used heretofore to secure the arm to the bar.

20 The bar 15 is cut or slit from the edge thereof to provide a projecting lip 17, which, when the parts are assembled, and the bar is slipped within the bore of the supporting arm, as far as is expedient, may be bent or turned about the strengthening brace 13 to secure the bar in position. It may be found expedient to provide the lip 17 upon that portion of the bar which is adjacent the lug 14, so that when the lip 17 is bent over the strengthening brace, it will come in contact with the lug 14 and thus a larger contacting surface is provided, and there will be more resistance offered to any relative movement of the parts. It will be obvious that when both ends of the bar are thus secured to the supporting arm and tip, that there will be provided an efficient connection between the parts and that all danger of relative movement or dislocation or separation of the parts will be avoided. Moreover, the connection provided is an expedient one from the standpoint of economy, for no nail or screw, pin or separate securing means is required, and in addition the use of the wooden plug which has been used heretofore in connection with all handles of this type is obviated. While I have chosen to show my improved connecting means as applied to a structure wherein the supporting arm and tip are cast in one piece, it will be understood that the same means may be used for connecting the bar to the supporting arm in casket handles of other types.

55 In Fig. 5 I have shown a modified form of my invention wherein the lug 14, which is attached to the strengthening brace 13 of Fig. 3, has been omitted. The lip 17 which is struck up from the tubular bar in this case is turned or bent around the strengthening rib, as clearly shown in Fig. 6, so that a firm contact is made between the parts, although the lug 14 of Fig. 3 has been omitted. In Fig. 9 I have shown still another form of my invention wherein the

strengthening brace, while not provided with the lug 14, is provided with a small recess or depression 19, which is of sufficient width to receive the lip 17 therein and when the lip is turned or bent into this recess, it will be apparent that the bar 15 may not rotate within the bore of the supporting arm, but will be secured firmly against rotary movement within the arm as well as against longitudinal movement. 75

In Fig. 10 I have shown still another form of my invention wherein the lip 17 is provided at such portion of the tubular bar that it may be bent or turned around the strengthening brace 13 just below the lug 14, so that this lip will be locked between the soft metal portion of the supporting arm and the lug 14. It is seen that this will also be an efficient means for preventing any tendency of the bar to rotate or turn within the arm. The tip is shown in this figure as provided with a recess 20, which allows the insertion of a tool, such as a screwdriver or the like, with which the lip 17 may be bent up around the strengthening brace 13 after the parts have been assembled. It may be here stated that it is usual in the assembly of the parts in all of the forms shown for the slits to be made upon each side of the lip 17 before the bar is inserted into the bore of the arm, but this lip remains in its original position with the periphery of the tubular bar 13 until this bar is slipped within the bore of the supporting arm and the parts are assembled. 100 Then the lip 17 is bent up by a suitable tool into engagement with the strengthening brace. 95

In Fig. 11 I have shown still another modified form of my invention. In some forms of casket handles it is usual to continue the soft metal portion of the tip to extend on the opposite side of the brace 13, so that the loop portion of the brace will be entirely surrounded by the soft metal. 110 My improved connecting means between the supporting arm and bar can be readily adapted to this form of arm and tip by providing the soft metal portion of the tip with a recess 21, which is adapted to receive the lip 17, which is then bent around to snugly engage a portion of the soft metal of the tip. It will be obvious that this will provide a convenient and effectual fastening between the parts, which will prevent 115 all relative movement therebetween and will, of course, allow no rotation of the bar within the arm. The recess 20 may obviously be provided in connection with all of the modifications shown, if desired. 120

In Figs. 12 and 13, I have shown a further modification of my invention in which the tube or bar 15 is shown as slit at two places, thus providing the two lips 17^a and 17^b, which when the bar is slit within the 130

loop portion of the arm and tip, may be bent up into engagement with the arm to secure the parts together. As clearly shown in Fig. 13, the lug 17^a is provided at such a point on the bar, so that it will, when turned up about the strengthening arm 13, contact laterally with the soft metal arm at the lower side of the bar and prevent relative rotation of the arm and bar in one direction. The other lip 17^b is provided near the upper portion of the bar, so that when it is turned up, as shown in Fig. 13, it will contact with the upper part of the soft metal arm and thus secure the arm and bar against relative rotation in the opposite direction. It will be seen that this connection will be an effectual one, and will prevent any relative movement between the casting, which comprises the arm and tip, and the bar.

While I have illustrated and described with particularity preferred forms of my invention, it is to be understood that the same is not to be limited to all of the details shown, but is capable of many modifications and variations which will lie within the spirit of the invention and within the scope of the appended claims.

What I claim is:

30 1. In a casket handle, a handle bar, and a supporting arm provided with a bore to receive said bar, an integral portion of one of said members embracing a portion of the other member to secure said members together.

2. In a casket handle, a handle bar and a supporting arm provided with a bore to receive said bar, a portion of one of said members being bent to embrace a portion of the other member.

3. In a casket handle, a handle bar, a supporting arm therefor including a strengthening brace, and a lip provided upon said bar and turned around said brace to secure the parts together.

4. A casket handle, including a handle bar, an integral arm and tip for said bar, the end of the bar being adapted to be received within the arm and tip, and a lip struck up from said bar and embracing a portion of said arm to prevent separation of said parts.

5. A casket handle including a handle bar, an integrally cast arm and tip for said

bar, the end of said bar being adapted to 55 enter said arm and lodge against said tip to limit relative movement of the parts in one direction, and means upon said bar to engage the arm to limit relative movement in the opposite direction.

6. A casket handle including a handle bar, an integrally cast arm and tip for said bar and interengaging means formed with the bar and casting to lock said parts together without the interposition of a third member.

7. A casket handle including a handle bar, a supporting arm therefor, an integral tongue on one of said members embracing a portion of the other member to prevent longitudinal movement of the bar relative to the arm and means to prevent relative rotation of said members.

8. A casket handle including a handle bar, a supporting arm therefor and interengaging means upon said arm and bar and formed integrally therewith to secure said parts against relative longitudinal and rotary movement.

9. A casket handle including a handle bar, an integrally cast arm and tip for said bar and means upon said bar to embrace a portion of said casting to secure said parts together.

10. A casket handle including a handle bar, an arm provided with a bore through which the bar is inserted, and means for interengaging a portion of the arm with a portion of the bar to lock the parts together.

11. A casket handle comprising a handle bar, an integrally cast arm and tip for said bar, and means to secure said bar to a portion of the tip whereby the bar will be supported by the arm.

12. A casket handle comprising a handle bar, a supporting arm for said bar, said arm carrying a tip, and cooperating interengaging means upon said bar and tip to secure the parts together.

13. In a casket handle, a handle bar, a supporting arm therefor and a lip integrally formed on one member and engaging a part of the other member to secure said members together.

In witness whereof, I have hereunto set my hand this 25 day of February, 1921.

EDWARD R. SARGENT.
